UNITED STATES PATENT OFFICE.

CHARLES T. DUFFEY, OF CAMBRIDGE, OHIO.

MOVING-PICTURE-FILM REEL.

1,164,999.

Specification of Letters Patent. Patented Dec. 21, 1915.

Application filed February 12, 1914. Serial No. 818,369.

To all whom it may concern:

Be it known that I, CHARLES T. DUFFEY, a citizen of the United States, residing at Cambridge, in the county of Guernsey and State of Ohio, have invented new and useful Improvements in Moving-Picture-Film Reels, of which the following is a specification.

The invention relates generally to an improvement in moving picture film reels, and particularly to the combination with a spool of such a reel of a film grip, in the use of which the film may be readily applied to or removed from the spool with the grip operative from the side plates of the reel.

The main object of the present invention is the provision of a film grip in the use of which by reason of its simplicity of operation and function, the film may be threaded under practically any and all conditions, while the specific structure of the grip insures its perfect action and effectiveness as long as the reel remains in use.

The invention in the preferred form of details will be described in the following specification, reference being had particularly to the accompanying drawings, in which:

Figure 1 is a plan view of the spool, side plates being omitted. Fig. 2 is a vertical central section on line 2—2 of Fig. 1. Fig. 3 is a transverse section taken through the push rod.

In carrying out the improvement, I secured upon the surface of the spool 1 a spring strip 2, said spring being secured in place through the medium of the screw 3 passing through the strip and taking into the spool, the connection being intermediate the ends of the strip, so as to provide free gripping ends 4. The spring strip conforms to the shape of the spool and snugly fits the same, being approximately equal in length to one-third the circumferential length of the spool, though these proportions are merely illustrative of a desirable arrangement.

The spool proper at a point intermediate the gripping end and screw connection of the spring strip is bored for a portion of its length and from opposite sides to provide a cylindrical recess 5, opening through the end of the spool and terminating short of its median diameter line. The recesses 5 are arranged on opposite sides of the screw 3, that is each recess is between the screw and

one gripping end of the spring strip being located more particularly so that a recess for operating the gripping end of the spool is with respect to the screw connection located reverse to the direction of rotation of the reel. The spool is further formed with an auxiliary recess 6 forming a continuation of each recess 5 and extending axially of the spool to a point beyond the medium line 60 thereof, the recess 5 communicating with the recess 6 with the latter concentric with the former. In the recess 5 is secured a sleeve 7 having an initially extending annular flange 8 at its inner end the sleeve corresponding in length to the length of the recess 5 and the opening of the flange 8 forming a guide for the reception of the push rod 9, terminating in a button 10 at the outer end, the spring 11 encircling the push rod and bearing between the button and flange 8, the spring serving to normally maintain the push rod at the limit of outer movement. The push rod more or less accurately fits for sliding movement the recess 6, and at its inner end is formed to present a beveled surface 12. Beneath each section of the spring strip intermediate the screw 3 and gripping end 4 is arranged a bore 13 communicating at its lower end with the recess 6. A sleeve 14 is snugly fitted in the bore 13 and the pin 15 slidably fitted in the sleeve, the lower end of the pin normally resting upon the push rod 9 and on the inclined surface thereof, the spring 11 80 so positioning the push rod as to maintain the latter in such relation to the pin as to cause the latter to rest upon the inclined surface adjacent the relatively inner or lower end thereof.

The side plates 17 which together with the spool completes the reel, are secured in place through the medium of screws 18 said side plate being formed with openings 19 to register with the respective buttons 10. The openings 19 are slightly smaller than the buttons to prevent complete projection of the latter therethrough, the convex surface of the buttons projecting sufficiently through the openings for operation.

The use of the improvement will be obvious from the above description, taken in connection with the drawings, it being obvious that upon pressure upon either push rod the pin coöperating therewith will be elevated to force the gripping end of the spring from contact with the spool surface

thereby permitting ready insertion or withdrawal of the film end. The improvement is extremely simple, permits coöperation of the gripping mechanism from either side of the reel without the necessity of inserting the hands between the plates for lifting the spring, and by reason of its coöperation with the spring to lift the latter just a desired distance from the spool surface prevents dis-
10 tortion of the spring.

What is claimed is:—

1. The combination with a reel spool, of a film gripping spring secured thereon, and means involving distinct elements and movable axially of and at right angles to the axis of the spool for raising said spring from gripping coöperation with the spool surface.

2. The combination with a reel spool, of a gripping spring secured thereon, a lifting element movable at right angles to the axis of the spool and coöoperating with the spring, and an operating element movable axially of the spool and coöoperating with the lifting element in movement of said operating
25 element in one direction.

3. The combination with the reel spool and side plates removably secured thereto, of a spring arranged on and conforming to the surface of the spool, said spring being secured intermediate its ends and the spool to provide gripping ends of the spring terminals, means operative in the spool and underlying the gripping ends of the spring, and operating elements for said means, said
30 elements being movable axially of the spool and limited in their inoperative movement by the said plates.

4. The combination with the reel spool and side plates removably secured thereto, of a spring arranged on and conforming to the surface of the spool, said spring being secured intermediate its ends and the spool to provide gripping ends of the spring terminals, means operative in the spool and under-
40 nly

45 lying the gripping ends of the spring, and operating elements for said means, said elements moving axially of the spool and being operative through the side plates, said side

plates limiting the inoperative movement of said elements.

5. The combination with a reel spool and side plates therefor, of a gripping spring secured to the spool, and a push rod operative in the spool and adapted in movement in one direction to elevate the spring, said push rod having a head end accessible through an opening formed in one of the side plates and coöperating with the edges of said opening to limit the inoperative movement of the push rod.

6. The combination with a reel spool and side plates therefor, of a gripping spring secured to the spool, and a push rod operative in the spool and adapted in movement in one direction to elevate the spring, said push rod having a head end accessible through an opening formed in one of the side plates and coöperating with the edges of said opening to limit the inoperative movement of the push rod, said head end being rounded to normally project in part through the opening in the side plate to permit operation of said push rod.

7. A reel for films and the like comprising a hub having a recess parallel with its axis and a bore at right angles thereto, and terminating in said recess, a member movable in said recess and having an inclined surface, a film gripping spring on the hub, and a member movable in the said bore for co-operation with said inclined surface and engageable with said spring to raise the same.

8. The combination with a reel spool, of a film gripping spring, and means involving distinct elements and movable axially of and at right angles to the axis of the spool and accessible from the outside of the spool for moving said spring from gripping coöperation with the spool surface.

In testimony whereof I affix my signature in presence of two witnesses.

CHARLES T. DUFFEY.
